UNITED STATES PATENT OFFICE.

ROBERT CARDWELL, OF LIVERPOOL, AND SAMUEL WATSON, OF MANCHESTER, ENGLAND.

RAIL-CHAIR AND COUPLING FOR PERMANENT WAYS.

SPECIFICATION forming part of Letters Patent No. 478,399, dated July 5, 1892.

Application filed January 12, 1892. Serial No. 417,895. (No model.)

To all whom it may concern.

Be it known that we, ROBERT CARDWELL, residing at Liverpool, and SAMUEL WATSON, residing at Manchester, in the county of Lancaster, England, subjects of the Queen of Great Britain, have invented new and useful Improvements in Rail-Chairs and Couplings for Permanent Ways, of which the following is a specification.

- 10 Our invention relates to improvements in rail-chairs and couplings for permanent ways, (for which Letters Patent dated October 15, 1889, and numbered 412,834, were granted to us,) and in which invention the rail in its continuity or at its ends is secured, respectively, either to a single or joint chair by means of a hinged jaw, in combination with a metal wedge driven between the same and projections formed on the base of the chair.
- 15 The object of our invention is to render the said hinged jaw readily detachable, and thereby facilitate the placing and removal of the rail or rails on or from the chair, while at the same time the hinged jaw is prevented from becoming fast through corrosion and will adjust itself against and thus hold the rail more firmly than heretofore has been the case. We attain these objects by the mechanism illustrated in the accompanying sheet of drawings, in which—

Figure 1 is a side view, and Fig. 2 a plan, of a rail-chair constructed in accordance with our invention and adapted to be secured to a sleeper. Fig. 3 is a sectional side view, and Fig. 4 a plan, of a chair with rail and hinged jaw removed. Figs. 5 and 6 are respectively a side view and back view of the hinged jaw itself detached.

Similar letters refer to similar parts throughout the several views.

In carrying out our invention and referring

to the figures generally we dispense with the bolt used heretofore to secure the movable jaw *a* to the base *b* of the chair, and form the movable jaw *a* at each end with a pivot *c*, (see 45 more particularly Figs. 5 and 6,) preferably by casting a metal pin into the same, the ends of which project on each side thereof. The eyes *d* we form solid and the inner sides with a slotted socket *e e'*, adapted to receive the 50 pivots *c* of the movable jaw *a* when placed between the eyes *d*, thus forming a slot-hinge. The wedge *g*, placed between the projections or noses *f f*, when driven home forces the movable jaw *a* bodily against the side of the rail 55 *r*, and when withdrawn the jaw *a* may be readily removed by throwing back and lifting it out of the socket *e* through slot *e'*.

It will be understood that the improvements described are applicable for single as well as 60 joint chairs either secured to or formed with a sleeper.

What we claim as our invention, and desire to secure by Letters Patent, is—

In single and joint rail-chairs secured to or 65 formed with a sleeper, the movable jaw *a*, having pivots *c*, in combination with eyes *d*, formed on the base *b*, the inner faces of which are formed with slotted sockets *e e'*, adapted to receive the pivots *c* and serve as a fulcrum 70 for the movable jaw *a*, substantially as and for the purpose set forth.

This specification signed and witnessed the 28th day of December, 1891.

ROBERT ^{his} CARDWELL.
SAMUEL ^{mark} WATSON.
